(57) **CLAIM**

The ornamental design for a wrap with pockets, as shown and described.

DESCRIPTION

The claimed wrap with pockets is a garment to be wrapped or folded about a person.

FIG. 1 is a front elevational view of a wrap with pockets showing my new design;

FIG. 2 is a left side view thereof; the right side view being a mirror image of the left side view; and,

FIG. 3 is a top plan view thereof; the bottom plan view being a mirror image of the top plan view.

1 Claim, 2 Drawing Sheets

FIG. 1

FIG. 2

FIG. 3
